DOUBLE-FREQUENCY PHASE-ANGLE
RELAYING SYSTEM

Herbert W. Lensner, East Orange, N. J., assignor
to Westinghouse Electric Corporation, East
Pittsburgh, Pa., a corporation of Pennsylvania

Application October 30, 1947, Serial No. 783,161

4 Claims. (Cl. 175—294)

1

My invention relates to phase-angle, or phase-comparing, carrier-current protective-relaying systems for protecting transmission-lines against faults.

The principal object of my invention is to make such relaying-systems more reliable in their operation, when operating at two different carrier-frequencies, or to provide a reliable system which is operative at either one carrier-frequency or two carrier-frequencies.

For some years past, commercial use has been made of a phase-comparing protective-relaying system, the latest form of which is described and claimed in a joint application of S. L. Goldsborough, R. C. Cheek and myself, Serial No. 758,200, filed June 30, 1947. In such systems, a succession of bursts of carrier-current impulses are transmitted during alternate half-cycles of the line-current, whereas, during the intervening half-cycles, operating-current impulses are applied to a relay. The received carrier-current energy is used to prevent the effective application of the operating-current impulses to the relay during the times when carrier-current energy is being effectively received. The actual operating-current which is applied to the relay is supposed or assumed to be zero, under an ideal through-fault condition, that is, when the in-looking line-currents at the two line-terminals are 180° out-of-phase with each other. When this 180° phase-relation is departed from, the relay is supposed to receive longer and longer portions of the half-wave operating-current impulses, until, at the 0° phase-relation, the relay receives each operating impulse during the full half-cycle of its duration.

When such a phase-angle-comparing carrier-current system is operated at two different carrier-current frequencies (the transmitter being tuned to one frequency, and the receiver being tuned to another frequency), the relay-current does not drop to zero, under an ideal through-fault condition. On the contrary, cases have been observed, in which the relay-current under these conditions has been as much as 50 to 60% of the pickup value of the relay, thus creating a hazard of faulty operation in systems in which the relay is given a particularly sensitive setting, or in cases where the relay-current may possibly reach the pickup value during a through-fault condition.

The reason for this difficulty is that the incoming half-cycles of carrier-current energy have an envelope which has an essentially square-topped 60-cycle wave-form, which means

infinite harmonics of 60 cycles in the received signal. The tuned circuits of the receiver will not pass the higher harmonics of 60 cycles, and hence will not pass the square wave, with the result that the restraining voltage which is applied to the relay tube from the receiver will increase only gradually, at the beginning of each restraining-impulse half-cycle. The operating voltage, however, has a square 60-cycle wave-form, so that it increases suddenly to its final value, resulting in portions of a half-cycle during which the application of the operating voltage is not offset by the restraining-voltage.

With single-frequency operation, that is, with both the transmitter and the receiver operating at the same carrier-frequency, the carrier-receiver theoretically receives essentially a continuous signal during ideal through-fault conditions, so that the restraint-voltage will be steady, and of a substantially constant value, so that there will be no operating-voltage applied to the relay.

An object of my present invention is to provide a delayed-build-up means, for delaying the building up of the operating impulses in the relay, without substantially delaying the decay of these operating-impulses, thus permitting the effective operating-current of the relay to become zero during ideal through-fault conditions.

With the foregoing and other objects in view, my invention consists in the system, circuits, combinations, elements and methods of design and operation, which are hereinafter described and claimed, and illustrated in the accompanying drawing, the single figure of which is a much simplified diagrammatic view of circuits and apparatus illustrative of my invention in a preferred form of embodiment.

In the drawing, I have illustrated my invention as applied to one terminal of a line-section 1 of a 3-phase transmission-line, which is connected to a 3-phase station-bus 2 by means of a circuit-breaker 3 having a trip-coil TC and an auxiliary make-contact 3a. I have shown only one terminal of the protected line-section 1, with the understanding that the other terminal is, or may be, a duplicate of the terminal equipment which is illustrated, except for a different carrier-current frequency, as will be subsequently noted.

I have illustrated a system using a bank of line-current transformers 4, which respond to the 3-phase line-current in the protected line-section 1, and I supply this current to any suit-

able network or filter, which is marked HCB, for deriving a single-phase alternating-current voltage which is applied to the primary winding of a saturable transformer ST. Any suitable network, such as HCB, may be utilized, for deriving a single-phase relaying current or voltage which is reasonably uniformly responsive to a plurality of kinds and severities of faults on whatever line-phase a fault may occur. The secondary winding 6 of the saturable transformer ST is shunted by a voltage-limiting gas-filled tube GT-1, as described in the Harder Patent 2,183,646, granted December 19, 1939.

The secondary winding 6 is used to control two mechanical fault-detector relays FD1 and FD2 having diverse sensitivity-settings, and also to control two alternately triggering gas-filled tubes V1 and V2, as described in the copending joint application. The operating-coils of the two fault-detector relays FD1 and FD2 are shown as being energized in series with each other, from the output-terminals of a rectifier-bridge RB, which is supplied with energy from the secondary winding 6 of the saturating transformer ST. The gas-filled tubes V1 and V2 are controlled from the aforesaid secondary winding 6 by having the tube-grids G1 and G2 energized, through resistors R1 and R2, from two secondary windings 11 and 12 of an input-transformer IT, the primary of which is energized from the secondary winding 6 of the saturated transformer ST. The other two terminals of the secondary windings 11 and 12 of the input-transformer IT are shown as being connected together, in a circuit 14 which is connected to an intermediate tapped-point of a cathode-circuit biasing-resistor R3, which is in the cathode-circuits of the gas-tubes V1 and V2.

As shown in the drawing, one terminal of the cathode-circuit biasing-resistor R3 is connected to the negative bus (—) of a direct-current voltage-source for the tubes, while the other terminal of said resistor is connected to a conductor 15, which is used for several purposes. The circuit 15 is used to energize one terminal of a cathode-circuit loading-resistor R4, the other terminal of which is connected to the cathode-terminal 21 of the first, or carrier-starting, gas-tube V1. The circuit 15 is also utilized to energize one terminal of another cathode-circuit loading-resistor R5, the other terminal of which is connected to the cathode-circuit 22 of the second, or relay-energizing, gas-tube V2.

The two grid-terminals of these tubes V1 and V2 are connected to their respective cathode-circuits 21 and 22 through capacitors C1 and C2, as is known in the art. The two plate-circuits P1 and P2 of these two tubes are connected together through a capacitor C3 which assists in firing-transfer. The two cathode-circuit loading-resistors R4 and R5 are respectively shunted by capacitors C4 and C5, which also assist in firing-transfer. The circuit 14, which is connected to an intermediate tap of the cathode-circuit biasing-resistor R3, is also connected to the circuits of the screen grids SG1 and SG2 of the respective gas-tubes V1 and V2. The two plate or anode-circuits P1 and P2 of the two gas-tubes are connected, respectively, through resistors R6 and R7, to a common conductor 24, which is in turn connected to the positive bus (+) through a resistor R8.

The two alternately firing gas-tubes V1 and V2 are supervised by the low-set fault-detector FD1, by having the positive tube-circuit 24 connected to the negative terminal (—) through the

normally closed back-contact 25 of the low-set fault-detector FD1.

The circuits of the several relays which are used in my invention are arranged, as far as practicable, after the manner of a schematic diagram or "across-the-line" diagram. In each case, the main or operating coil of the relay is given a letter-designation or legend, and the same letter-designation or legend is applied to all of the contacts of that relay. The relays and switches are invariably shown in their open or deenergized positions. Arrows are used to symbolically indicate how the various parts of each relay are connected together.

The back-contact 25 of the low-set fault-detector FD1 is also used to control the energization of an auxiliary relay K, by having the operating-coil K of this auxiliary relay connected, through a resistor R9, across the FD1 back-contact. The auxiliary relay K has a single back-contact K, which is connected in series with a telemetering key TM, which is indicated by way of illustration of carrier-current control for purposes other than relaying. The auxiliary-relay back-contact K thus acts substantially like a back-contact placed upon the low-set fault-detector FD1, said auxiliary relay K being utilized for supplying this contact in order to avoid mechanically overloading the low-energy fault-detector FD1.

The cathode-circuits 21 and 22 of the respective gas-filled tubes V1 and V2 are used as sources of two alternating series of square-topped positive-voltage impulses, for two different purposes. These positive-voltage impulses are the voltage-drops through the respective cathode-circuit loading-resistors R4 and R5, which have voltage-drops therein when their respective tubes V1 and V2 are firing.

The cathode-circuit 21 of the first gas tube V1 is used to energize the plate-circuit P3 of a carrier-current master-oscillator tube OSC, through a radio-frequency choke-coil RFC-1. This oscillator-tube OSC serves as a carrier-current transmitter for transmitting a succession of bursts of substantially square-topped, or unmodulated, carrier-frequency impulses to the other line-section terminal (not shown), as will be subsequently described. During fault-free conditions of the transmission-system, the gas-tubes V1 and V2 are not firing, because of the short-circuiting back-contact FD1, and at such times the carrier-current oscillator OSC may be energized through the telemetering key TM, and the back-contact K, which connect the circuit 21 to the positive bus (+) through a resistor R-10.

The transmitter-oscillator OSC has its screen-grid SG3 connected to the plate-supply circuit 21 of said oscillator. The cathode-circuit of the oscillator OSC is the previously-mentioned circuit or conductor 15. The oscillator has a grid-circuit G3, which is connected to the cathode-circuit 15 through a grid-resistor R-11.

The plate-circuit P3 of the oscillator OSC is connected, through a blocking-capacitor BC1, to an intermediate terminal 27 of a tuned carrier-frequency circuit which determines the carrier-current frequency of the transmitter. This tuned circuit comprises the conductor 27, a capacitor C6, a conductor 28, a capacitor C1, the cathode-circuit 15, a capacitor C8, the grid-circuit G3, and a variometer L1, the other terminal of which is connected to the starting-point 27 of the tuned circuit.

The conductors 28 and G3 of this tuned cir-

cuit are respectively utilized to apply radio- or carrier-frequency control-voltages, through blocking-capacitors BC2 and BC3 respectively, to the grids of two amplifier-tubes A1 and A2. The cathodes of the amplifiers A1 and A2 are connected to the cathode-circuit 15 of the oscillator OSC. The grids of the amplifier tubes A1 and A2 are connected, through grid-resistors GR1 and GR2, to the negative bus (-), so as to apply a negative bias equal to the drop across the cathode-circuit biasing-resistor R3. The two plates of the amplifiers A1 and A2 are connected to the primary-winding terminals of a radio-frequency output-transformer OT. The primary winding of said output-transformer OT has a midpoint tap 30 which is connected to the positive supply-terminal (+) and also to the screen-grids of the two amplifiers A1 and A2.

The radio-frequency output-transformer OT has a secondary winding 31, having one of its terminals grounded, and having two taps 32 and 33. The output-transformer secondary-tap 32 is connected to phase-C of the line 1, through a variometer L2, a conductor 34, and a coupler-capacitor CC. The conductor 34 is also grounded through a grounding-coil GC. The secondary tap 33 of the radio-frequency output-transformer OT is utilized to energize the primary winding of a receiver-coupling transformer RCT, through a tuning-capacitor T-C.

The radio-frequency of the tuned receiver-circuit (T-C, RCT) may, or may not, be different from the radio-frequency of the tuned transmitter-circuit (L1, C6, C7, C8), according to local conditions of the particular transmission-system in which the apparatus is installed. It is an object of my invention to provide a protective-relay system in which the carrier-current frequencies of the transmitter and the receiver may be either the same or different, as will be subsequently described.

The primary winding of the receiver-coupling transformer RCT is usually protected by a shunt-connected voltage-limiting gas-filled tube GT-2.

The receiver-coupling transformer RCT has a secondary winding 36 which is part of another tuned receiving-circuit, comprising said secondary winding 36, the grid-conductor G4 of a receiver-tube REC, a tuning-capacitor C9, the circuit or conductor 15, and thence back to the secondary winding 36.

The receiver-tube REC is a saturating-tube which carries a plate-cathode current which is of a substantially constant magnitude, whenever the tube is conducting at all, substantially regardless of the voltage applied to the grid-circuit G4, provided that this grid-voltage is high enough to cause plate-current to flow.

The receiver-tube REC has its cathode-circuit 37 energized from a tapped point of a potentiometer PO4 which is connected between the circuit 15 and the positive bus (+). The receiver-tube REC has a plate circuit P4, which is energized from the positive supply-terminal (+) through a radio-frequency choke-coil RFC-2. In the drawing illustrative of my invention, I have symbolically shown the telemetering relays 38 in series with the plate-circuit P4, although it should be understood that, in general, the telemetering relays 38 would be used only at one line-terminal, while the telemetering key TM would be used at the other line-terminal. The receiver-relay REC also has a screen-grid circuit SG4 which is connected to the positive terminal (+).

The receiver-relay plate-circuit P4 is used to apply a restraining voltage to the grid-circuit G5 of a relay-tube RT, through a coupling-capacitor C-10, a conductor 39, a voltage-doubler which is generically indicated at 40, and a grid-circuit resistor R-12. The voltage-doubler 40 consists of an input-resistor R-13 which is connected to the conductor 39, a capacitor C11, which is connected between the circuit 39 and a circuit 41, a double-circuit rectifier-valve RV, and an output-resistor or loading-resistor R-14. The loading-resistor R-14 is connected between the anode-circuit 42 of the right-hand rectifier of the rectifier-valve RV, and a circuit 43 which is connected to the input-resistor R-13. The anode-circuit 42 also constitutes the input-terminal of the grid-circuit resistor R-12 of the receiver-tube RT. The cathode of the right-hand half of the double-rectifier valve RV is connected to the conductor 41, while the anode of the left-hand rectifier-circuit of the double valve RV is connected to this same conductor. The cathode of the left-hand rectifier of the double valve RV is connected to the circuit 43 between the input and output-resistors R-13 and R-14. The output-resistor R-14 of the voltage-doubler is by-passed by a ripple-smoothing radio-frequency by-pass capacitor BPC.

In accordance with my present invention, I provide a delayed-build-up means, which is essentially a low-pass filter (L and C) shunted by a rectifier 44. This low-pass filter is connected between the cathode-circuit 22 of the second gas-tube V2 and the circuit 43 of the voltage-doubler 40. The filter-inductance L, and the rectifier 44 are connected, in parallel-circuit relation to each other, between the circuits 22 and 43, with the rectifier 44 in such polarity that it conducts current in the direction from the circuit 43 to the circuit 22. The filter-capacitor C is connected between the circuits 43 and 15.

The relay-tube RT has its cathode-circuit 45 energized from a tapped point of a potentiometer PO5 which is connected between the conductor 15 and the positive supply-terminal (+). The plate-circuit P5 of the relay-tube RT is connected through the primary winding of a relay output-transformer ROT, a conductor 46, a make-contact 47 of the high-set fault-detector FD2, and thence to the positive terminal (+). The screen-grid circuit SG5 of the relay-tube RT is also connected to the aforesaid conductor 46.

The relay output-transformer ROT has a secondary winding 48, which is used to energize the operating coil R of a relay R which has a single make-contact 49, which is shown, near the top of the negative supply-terminal (-), as being in the tripping-circuit of the trip-coil TC of the circuit breaker 3, this trip-circuit extending from the negative bus (-) to the positive bus (+), and also including the auxiliary breaker-contact 3a.

Before describing the operation of the novel features of my invention, I will first describe the general operation of the carrier-current protective-relay system. When a fault of a predetermined severity occurs on the protected line-section 1, one or both of the two fault-detectors FD1 and FD2 will pick up. The low-set detector FD1 is the more sensitive of the two, and when it responds, it opens its back-contact 25, and thus removes a short-circuit from around the two gas tubes V1 and V2. The grid-circuit setting of these gas-tubes V1 and V2 is such that said tubes are already in readiness to fire, in response

to the alternating voltages which are applied to their respective grids G1 and G2.

Whichever one of the two gas tubes V1 and V2 has a positive grid voltage applied to it, at the moment of opening of the FDI back-contact 25, will instantly begin firing, developing a certain positive voltage in its cathode-circuit 21 or 22, as the case may be, making said cathode-circuit positive with respect to the conductor 15. During the next half-cycle of the line-current, or output of the secondary winding 6 of the saturating transformer ST, a positive grid-voltage is applied to the other one of the two gas-tubes V1 and V2, causing this other tube to fire, putting out the first-firing gas-tube, in the process. The two gas-tubes V1 and V2 thus operate as sources of two different series of flat-topped voltage-waves of constant magnitude, one gas tube being responsive to positive line-frequency half-cycles, while the other is responsive to negative line-frequency half-cycles.

Carrier-current is transmitted by the conducting or operation of the master-oscillator tube OSC during the flat-topped voltage impulses which are supplied from the cathode-circuit 21 of the first gas-tube V1, thus transmitting a succession of bursts of carrier-current energy, which are applied to the line through the coupling capacitors CC, during line-current half-cycles of one polarity. During the line-current half-cycles of the other polarity, positive or operating-voltage is applied to the grid-circuit G5 of the relay-tube RT through the cathode-circuit 22 of the second gas-tube V2, the voltage of the circuit 22 being applied to the grid-circuit G5 through my newly added delayed-build-up means (L, C, 44) and the output-resistor R-14 of the receiver-energized voltage-doubler 40. The operating-voltage, which is applied to the relay-tube RT by the circuit 22, tends to cause the flow of plate-current in the relay-tube RT.

If the carrier-frequencies of the transmitter and receiver are identical, the carrier-current impulses which are transmitted from both ends of the protected line-section are received in the receiver-tube REC at each end of the line-section, but if the transmitter and receiver frequencies are different, each receiver receives only the impulses which are transmitted from the other line-terminal. The only important received carrier-impulses, at either end, are those which are received from the other terminal, or from the far end of the protected-line section, because the carrier-current impulses, or bursts, or operating-periods, which are transmitted from the relaying station itself, always occur during the half-cycles of the line-current when no operating-voltage is applied to the grid-circuit G5 of the relay-tube RT from the cathode-circuit 22 of the second gas tube V2. At the far end of the protected line-section, however, the carrier-current energy-impulses or bursts, which are transmitted at line-frequency half-cycle intervals, are transmitted in response to the cathode-circuit 21 of the first gas tube V1 in that station, so that, if the in-looking line-current at the far-end station is 180° out of phase with the line-current at the relaying station (as it will be, on short lines of moderate voltage, when there is no fault in the protected line section), then the carrier-current transmitting-periods at the far end will exactly coincide with the operating-voltage half-cycle periods at the relaying station, and thus they will theoretically block a response of the relay-tube RT.

The received carrier-current energy is applied, in a blocking fashion, to the grid-circuit G5 of the relay-tube RT, through the coupling capacitor C-10 and the voltage-doubler 40, which operates to build up a negative voltage, in the loading-resistor R-14, which is at least as large as, and opposite in sign to, the positive grid-voltage which is supplied by the cathod-circuit 22 of the second gas tube V2.

The result of the foregoing operations is that the relay-tube RT will become conducting only when there is an internal fault, or a fault within the protected line-section 1, in which case the tube will become conducting periodically, in short or long bursts, depending upon the phase-relations between the line-currents at the opposite ends of the protected line-section. Troublesome phase-relations may exist between the opposite-end line-currents during through-fault conditions, even in the case of single-frequency phase-angle relaying-systems, if the line-voltage is particularly high, or if the line-section is particularly long. A high line-voltage may cause charging-currents which can make the total line-current at the sending end or power-source end lead the load-end current by an appreciable phase-angle. Also, if the line-section is unusually long, the propagation-time required for the carrier wave to travel from the load-end to the power end of the protected line-section can amount to an appreciable part of a line-frequency cycle, giving the effect of an appreciable line-frequency phase-angle shift. When these two effects are present concurrently, my time-delay network L-C-44 is usually needed, to prevent faulty operation, even in single-frequency phase-angle relaying-systems.

The alternating-current component of the plate-current of the relay-tube RT is applied to the operating coil of the phase-angle-responsive relay R, through the relay output-transformer ROT. The contact 48 of the relay R is then utilized to trip the breaker 3.

It will be noted that the carrier-current equipment acts as a pilot-channel connecting the two ends of the protected line-section for the purpose of effecting a determination or comparison of the phase-angle between the two terminal line-currents of the protected line-section.

My newly added low-pass filter (L, C) allows the square-topped operating-voltage impulses, which appear in the circuit 22, to build up only gradually, because the filter will not pass the higher harmonics of the square wave of the operating voltage. The filter thus delays the build-up of each operating-voltage impulse which is applied to the grid-circuit G5 of the relay-tube RT. This delayed build-up of the operating-voltage impulses is desirable, as previously explained, in order to match or exceed the delayed build-up of the receiver-responsive restraint-voltage impulses, due to the inability of the tuned receiver-circuits (T-C, RCT) and (36,C9) to pass these same high harmonics in the received square wave of carrier energy, which is particularly important in cases in which the carrier-current receiver is operating at a different carrier-current frequency than the transmitter.

If the low-pass filter (L, C) were used alone, without the shunt-connected rectifier 44, this filter would also delay the collapse or decay of each of the square-top operating-voltage impulses, which would be undesirable, because it would cause the application of an operating-

voltage to the tube during the first portion of the line-frequency half-cycle during which no operating-voltage was intended to be applied. To correct this condition, the rectifier 44 is connected across the inductance L of the filter, so as to allow the filter-voltage impulses to decay rapidly, by letting the filter-capacitor C discharge through the circuit including the conductor 43, the filter-shunting rectifier 44, the conductor 22, and the cathode-circuit resistor R5 of the gas-tube V2. For currents flowing in the other direction, the filter-shunting rectifier 44 has a sufficiently high resistance so that it has a negligible effect upon the rate of building-up of the operating-voltage impulses, as applied to the grid-circuit G4 of the relay-tube RT.

It will thus be seen that I have provided a means whereby a phase-comparing carrier-current protective-system may be operated with either a single carrier-current frequency or with different frequencies for the transmitter and the receiver, without the risk of a faulty relay-operation resulting from the failure of the receiver to pass the higher 60-cycle harmonics during double-frequency operation of the carrier-current protective-relay system.

While I have illustrated my invention, and described its application, in but a single form of embodiment, which has been chosen for illustrative purposes, I wish it to be understood that many changes of addition, substitution or deletion could be made, without departing from the essential spirit of my invention. I desire, therefore, that the appended claims shall be accorded the broadest construction consistent with their language.

I claim as my invention:

1. Terminal equipment for one terminal of a pilot-channel phase-angle relaying-system for an alternating-current line, comprising the combination, with a relay to be controlled, and a pilot-channel means for communicating with another terminal of the protected line-section, of means for deriving an alternating-current line-current quantity which is responsive to a plurality of different line-fault conditions, impulse-producing means for applying a succession of substantially square-topped operating-impulses and a succession of substantially square-topped pilot-channel-controlling impulses on alternate half-cycles of said derived line-current quantity, circuit-means, including a delayed-build-up means, for applying said succession of operating-impulses to said relay, said delayed-build-up means being operative to delay the

building-up of the operating-impulses in the relay without substantially delaying the decay thereof, means for delivering said pilot-channel-controlling impulses to the pilot-channel means, and receiving-means for applying restraining-impulses, effective on said relay, in response to pilot-channel impulses received from another terminal of the protected line-section.

2. Terminal equipment for one terminal of a pilot-channel phase-angle relaying-system for an alternating-current line, comprising a relay to be controlled, a carrier-current transmitter of one carrier-frequency coupled to the protected line-section, a carrier-current receiver of another carrier-frequency coupled to the protected line-section, means for deriving an alternating-current line-current quantity which is responsive to a plurality of different line-fault conditions, impulse-producing means for applying a succession of substantially square-topped operating-impulses and a succession of substantially square-topped transmitter-controlling impulses on alternate half-cycles of said derived line-current quantity, circuit-means, including a delayed-build-up means, for applying said succession of operating-impulses to said relay, said delayed-build-up means being operative to delay the building-up of the operating-impulses in the relay without substantially delaying the decay thereof, means for delivering said transmitter-controlling impulses to the transmitter, and means, responsive to the receiver, for applying restraining-impulses to said relay.

3. The invention as defined in claim 1, characterized by said delayed-build-up means comprising a low-pass filter and a shunt-connected rectifier.

4. The invention as defined in claim 2, characterized by said delayed-build-up means comprising a low-pass filter and a shunt-connected rectifier.
